CLAIM

The ornamental design for a sandal, as shown and described.

DESCRIPTION

FIG. 1 is a top view of a sandal;

FIG. 2 is a bottom view thereof;

FIG. 3 is a front view thereof;

FIG. 4 is a rear side view thereof;

FIG. 5 is a right side view thereof;

FIG. 6 is a left side thereof;

FIG. 7 is a perspective view thereof; and,

FIG. 8 is a top view thereof in an unsecured configuration. The broken lines depicting the sole on the bottom of the sandal in FIG. 2 form no part of the claim. The broken lines depicting a region on the unsecured portions of the sandal in FIG. 8 form no part of the claim. The broken lines depicting regions on the secured portions of the sandal in FIGS. 4 and 5 form no part of the claim.

1 Claim, 8 Drawing Sheets
